UNITED STATES PATENT OFFICE.

EDWIN LEE TOMLINSON, OF NORTH BRANCH, MICHIGAN.

DESIGN FOR A MUD-GUARD.

57,799.

Specification for Design. Patented May 3, 1921.

Application filed February 1, 1921. Serial No. 441,680. Term of patent 14 years.

To all whom it may concern:

Be it known that I, EDWIN L. TOMLINSON, a citizen of the United States, and a resident of North Branch, in the county of Lapeer and State of Michigan, have invented a new, original, and ornamental Design for a Mud-Guard, of which the following is a specification, reference being had to the accompanying drawing, forming part thereof.

The figure is a view in front elevation of a mud guard showing my new design.

I claim:

The ornamental design for a mud guard as shown.

EDWIN LEE TOMLINSON.
